UNITED STATES PATENT OFFICE.

HIRAM O. CONGER AND CHARLES W. McCUE, OF WARREN, OHIO.

RAIL.

1,378,767.

Specification of Letters Patent. Patented May 17, 1921.

Application filed June 9, 1919. Serial No. 302,676.

To all whom it may concern:

Be it known that we, HIRAM O. CONGER and CHARLES W. McCUE, citizens of the United States, residing at Warren, in the 5 county of Trumbull and State of Ohio, have invented new and useful Improvements in Rails, of which the following is a specification.

This invention relates to a rail and has 10 for its primary object to provide a rail of such a construction that that portion bolted to the tie will be permanently connected thereto and only that part removed that becomes worn in the use of the rail.

15 An object of the invention is to provide a rail of two parts, a base portion and a head portion so connected that the head portion may be removed when rendered useless due to wear.

20 Besides the above our invention is distinguished in the manner of arranging the base member with relation to the head member so that the joints between the rail sections will be materially reinforced.

25 With these and other objects in view the invention will be better understood from the following detailed description taken in connection with the accompanying drawing wherein:

30 Figure 1 is a diagrammatic view showing the relation of the head member and base member.

Fig. 2 is a vertical sectional view through our improved rail.

35 Fig. 3 is a perspective view of one end of the base member.

Fig. 4 is a perspective view of one end of the head member.

40 Again referring to the drawing illustrating one of the many forms in which our invention may be constructed, the numeral 1 designates the base member and the numeral 2 designates the head member. The head member 2 is provided with a pair of spaced 45 flanges 3 and 4 extending the entire length of the rail head. The construction of the flanges 3 and 4 is such that they provide therebetween a slightly tapering recess 5 for the reception of a correspondingly shaped 50 flange 6 on the base member 1 extending the length thereof.

At the juncture of the flange 6 with the base member 1, we provide ribs 7 and 8 co-operating with the sides of the flange 6 to form wedge shaped slots 9 engaging the correspondingly shaped edge portions 10 of the flanges 3 and 4. From this construction it will be seen that when the head member is arranged in place the members are prevented from lateral movement with relation to each other due to the co-operation of the flanges and also due to the co-operation of the flanges with the ribs 7 and 8. Thus in a very substantial manner the head member is effectively associated with the base 60 member and to increase this action, bolts 11 are provided which pass through all the flanges.

By constructing the rail according to our invention, the head portion may be readily 70 removed when the same becomes worn without the necessity of removing any spikes as the base member which is not subject to wear will remain in place permanently. This is a material saving when taking into 75 consideration the present cost of railroad ties; as the railroad ties are practically useless after the spikes have once been removed therefrom, and if retained in place the life thereof is very short.

80 A very important feature of our invention, as clearly shown in Fig. 1, consists of arranging the base and head members in such relation that the joints of the head members will be in a position substantially 85 in the middle of the base members and vice versa with relation to the joints of the base members. By this construction weak joints between the rails are eliminated.

It is of course to be understood that the 90 head member and base member may be associated in other relations than shown and the base member provided with two flanges and the head member with one flange instead of being constructed as shown in the drawing; 95 therefore we do not desire to be limited in any manner except as set forth in the claim hereunto appended.

Having described our invention, what we 100 claim is:

In a rail, a base provided with a central upwardly projecting flange and with ribs at

opposite sides of the flange and integrally connecting the same and the base, the upper edges of the ribs being inclined downwardly to the flange, and a head member provided with integral flanges at opposite sides of and equidistant from its transverse center, said flanges fitting tightly against the lateral faces of the flange of the base member

and having their lower edges inclined similarly to and in contact with the upper edges 10 of said ribs.

In testimony whereof we affix our signatures.

HIRAM O. CONGER.
CHARLES W. McCUE.
